UNITED STATES PATENT OFFICE.

NELSON GLODDY, OF HILLSBORO, NEW HAMPSHIRE.

GARMENT-FORM.

1,159,926.

Specification of Letters Patent.

Patented Nov. 9, 1915.

Application filed May 19, 1914. Serial No. 839,604.

To all whom it may concern:

Be it known that I, NELSON GLODDY, citizen of the United States, residing at Hillsboro, in the county of Hillsboro and State 5 of New Hampshire, have invented certain new and useful Improvements in Garment-Forms, of which the following is a specification.

This invention relates to improvements 10 in forms for garments, more particularly to undergarments, such as undershirts, drawers, stockings, and the like, and has for one of its objects to improve the construction and increase the efficiency and utility of 15 devices of this character.

Another object of the invention is to provide a simply constructed form in which the edges are of smooth metal rounded and symmetrical, and conforming in outline to 20 the garment with which they are associated.

With these and other objects in view the invention consists in certain novel features of construction as hereinafter shown and described and then specifically pointed out in 25 the claim; and in the drawings illustrative of the preferred embodiment of the invention, Figure 1 is a side elevation of the improved device arranged as a form for drying stockings. Fig. 2 is a transverse section 30 enlarged on the line 2—2 of Fig. 1. Fig. 3 is a view on a reduced scale of the improved device arranged as a form for supporting an undershirt. Fig. 4 is a view on a reduced scale of the improved device shown 35 arranged as a form for supporting a pair of drawers.

Corresponding and like parts are referred to in the following description and indicated in all the views of the drawings 40 by the same reference characters.

The improved device comprises a body represented conventionally at 10 and provided with a sheet metal binding represented at 11, preferably U-shaped trans- 45 versely and embracing portions of the sides of the body 10, as illustrated in Fig. 2.

The body 10 together with its binding 11 conforms in outline to the garment with which it is engaged, and thus stretches the 50 garment equally at all points. In Fig. 1 the body 10 together with its binding 11 is in the form of a stocking, while in Figs. 3 and 4 the device is shown respectively in the

form of an undershirt and a pair of drawers, the various forms being employed 55 to illustrate the fact that the device is applicable to garments of different sizes and forms without material structural change. The body 10 may be of any suitable material, but will preferably be of heavy card 60 board, or the like, while the binding 11 will be a continuous strip of sheet metal, preferably brass or the like, and smooth upon the outer face and rounded at the corners to prevent abrasion of the garment. 65

When employed as a drying form for larger garments such as shirts, drawers, and the like, the body will preferably be in sections hingedly united, as shown at 12, in Figs. 3 and 4, to facilitate inserting in the 70 garment and likewise to occupy less room when not in use. By this simple means the garment is held firmly in stretched position while being dried, and no danger exists of the rupture of the threads of the garment 75 by contact with the form. The body 10 provides the necessary stiffness and rigidity to the device, while the binding prevents abrasion or fracture of the threads of the garment. 80

In forms heretofore used constructed of wood, they are liable to fracture while the edges are liable to become roughened and to splinter or sliver and are thus rendered liable to tear the garments while being inserted therein or removed therefrom. With the improved device, all danger of fracture of the garments is avoided, and a strong durable form is produced which may be repeatedly used and wherein no danger exists 90 of breakage or fracture by rough usage or the shrinking of the garments. 85

The improved device is simple in construction, can be formed of any required shape or size and of any suitable material. 95

Having thus described the invention, what is claimed as new is:

In a garment form, coacting elements longitudinally tapered throughout the major portion of their length and each formed 100 from a piece of fibrous material having unbroken area, the said elements being normally disposed in a common plane with the inner edges thereof at the larger extremities of the said elements confronting and swing- 105 ingly connected at longitudinally spaced

points, the free extremities of said elements having straight outer end edges and being provided with straight and uninterrupted inner and outer edges with the outer edges arranged substantially parallel and the inner edges throughout the major portion of their length diverging outwardly, and a continuous metallic binding strip extending

around the free edges of each of said elements.

In testimony whereof I affix my signature in presence of two witnesses.

NELSON GLODDY. [L. s.]
